UNITED STATES PATENT OFFICE.

JAMES N. MOULTON, OF HAVERHILL, MASSACHUSETTS.

DESIGN FOR THE ORNAMENTATION OF INNER-SOLE LININGS.

SPECIFICATION forming part of Design No. 16,663, dated April 27, 1886.

Application filed December 26, 1885. Serial No. 186,840. Term of patent 7 years.

To all whom it may concern:

Be it known that I, JAMES N. MOULTON, of Haverhill, county of Essex, State of Massachusetts, have invented and produced a new and original Design for the Ornamentation of Inner-Sole Linings for Boots and Shoes, of which the following is a specification, reference being had to the accompanying drawing, forming part thereof, the said drawing representing in plan view a lining ornamented according to my invention.

My design consists of an ornamental band or border, A, extending around the lining B near the edge thereof and equidistant from the edge, the said band or border being composed of lines which form a repetition of the letter

M, as shown in the drawing, the upright outside bars of the letters not being repeated between two adjoining letters, so that each of said bars forms part of two adjoining letters.

I claim—

The design for the ornamentation of inner-sole linings for boots and shoes herein shown and described, the same consisting of a band or border extending around the lining near the edge thereof, said band or border consisting of a repetition of the letter M, as set forth.

JAMES N. MOULTON.
